UNITED STATES PATENT OFFICE

WILLIAM REGINALD NICHOLSON, OF PANGBOURNE, ENGLAND

DESIGN FOR A BOTTLE

Application filed June 6, 1929, Serial No. 31,570, and in Great Britain February 15, 1929. Term of patent
14 years.

To all whom it may concern:

Be it known that I, WILLIAM REGINALD NICHOLSON, a subject of the King of England, residing at Tidmarsh Grange, Pangbourne, Berkshire, England, have invented a new, original, and ornamental Design for a Bottle, of which the following is a specification, reference being had to the accompanying drawing, forming part thereof.

Figure 1 is an elevational view, Figure 2 a side view, Figure 3 an under plan, and Figure 4 a plan view of the bottle, illustrating my new design.

I claim:

The ornamental design for a bottle as shown.

WILLIAM REGINALD NICHOLSON.
